UNITED STATES PATENT OFFICE.

HERMAN HERRENBRUCK AND FREDERICK ANDREAS, OF ST. LOUIS, MISSOURI,
ASSIGNORS TO BRIDGE & BEACH MFG. CO., OF ST. LOUIS, MISSOURI, A COR-
PORATION OF MISSOURI.

STOVE-DOOR.

1,311,891.

Specification of Letters Patent.

Patented Aug. 5, 1919.

Application filed February 15, 1919. Serial No. 277,215.

To all whom it may concern:

Be it known that we, HERMAN HERRENBRUCK and FREDERICK ANDREAS, citizens of the United States, residing in the city of St. Louis, State of Missouri, have invented a certain new and useful Improvement in Stove-Doors, of which the following is a full, clear, and exact description, such as will enable others skilled in the art to which it appertains to make and use the same.

This invention relates to pivotally mounted stove doors of the type that are equipped with a spring for counterbalancing the door.

One kind of stove door that is now in general use is provided with a trunnion that carries a forwardly projecting arm to which the lower end of a contractile spring is connected, said spring being arranged in a housing on the front side of the door frame and the upper end of said spring being connected to the upper end of the spring housing in such a manner that the spring is under tension at all times, both when the door is closed and open. The spring is apt to lose its resiliency or break quickly, due to the fact that it is always under tension, and it is apt to squeak or make a noise when it stretches, during the operation of opening the door. Accordingly, stove doors provided with contractile springs of the character referred to are a source of considerable annoyance to stove owners, dealers and manufacturers, as the springs have to be replaced frequently. Another objectionable characteristic of stove doors of the kind above referred to is that the spring housing on the door frame projects forwardly from the frame a considerable distance and detracts materially from the appearance of the stove.

The main object of our invention is to provide a spring operated stove door which is so constructed that the operating spring will not wear out quickly, break or make a noise when the door is being opened or closed.

Another object is to provide a spring operated stove door which is so constructed that the spring housing can be arranged in such a position that it does not detract from the appearance of the stove.

And still another object is to provide a stove door structure in which the removable portion of the spring housing is retained in position in a novel manner.

Figure 1 of the drawings is a front elevational view of a portion of a stove equipped with a spring operated stove door constructed in accordance with our invention; and

Fig. 2 is a vertical sectional view, taken on the line 2—2 of Fig. 1.

Referring to the drawings which illustrate the preferred form of our invention, A designates a pivotally mounted stove door, B the stationary frame that surrounds the opening which the door closes and C one of the trunnions on the lower edge of the door that forms part of the means for pivotally connecting the door to the door frame B.

The door A is counterbalanced by a compression spring D which exerts downward pressure on a rod 1 provided on its lower end with a fork or bifurcated portion 2 that engages a laterally-projecting pin 3 on an arm 4 which projects rearwardly from the trunnion C, the rod 1 projecting upwardly into the spring D, as shown in Fig. 2. Said spring D is arranged vertically in a spring housing E whose upper end serves as a stop or abutment for the upper end of said spring and the parts are so proportioned and arranged that the spring D is under little or no tension when the door is in its closed position, and will counterbalance the door during the operation of opening the door.

By referring to Fig. 2 it will be noted that the spring D is positioned at the rear side of the axis about which the door turns in a spring housing that projects rearwardly from the rear side of the door frame B. Consequently, the spring housing does not detract from the appearance of the stove, as the front side of said housing is flush or substantially flush with the front side of the door frame. In order that the spring D may be arranged easily in the spring housing E, during the operation of assembling the stove, the front wall of said housing is formed by a detachable section E' that is retained in position by a single bolt or other suitable fastening device. In the form of our invention herein shown the detachable section E' of the spring housing is provided at its upper end with a lug or hook 5 which projects rearwardly and upwardly through a hole in the top portion of the spring housing, as shown in Fig. 2, said lug being so shaped that it prevents the

upper end portion of the detachable section E' from moving outwardly. The lower end portion of the detachable section E' is retained in position by means of a bolt or 5 other suitable fastening device 6 that passes through said section and through the lower edge portion of the door frame B.

When the door is closed, as shown in Fig. 2, the spring D is under little or no tension, 10 said spring being arranged substantially parallel to the door A between the upper end of the spring housing E and the bifurcated portion 2 at the lower end of the guide rod.

1. When the door A is moved outwardly 15 into its open position the pin 3 on the rearwardly projecting arm 4 moves upwardly and thus places the spring D under tension, said spring being so designed that it will counterbalance the door when it is moving 20 to and from its open position. When the door A is fully open it is supported by a lug 7 on the detachable section E' of the spring housing that fits in a notch 8 in the door A.

Having thus described our invention, what 25 we claim and desire to secure by Letters Patent, is:

1. A stove door provided adjacent its 30 pivotal edge with a rearwardly-projecting arm, and a compression spring combined with said arm in such a manner that it will counterbalance the door and will be compressed when the door is moved into its open position.

2. A stove provided with a pivotally 35 mounted door, an arm projecting rearwardly from said door adjacent the axis about which the door turns, and a compression spring arranged at the rear of said axis at substantially a right angle to said arm and 40 in approximately parallel relation to said door for counterbalancing the door when it is moved to and from its open position.

3. A stove provided with a pivotally 45 mounted door, an arm projecting rearwardly from said door adjacent the hinged edge of same, and a counterbalancing compression spring for said door arranged in a housing on the door frame at one side of 50 said arm and in approximately parallel relation to the door, said arm causing said

spring to be compressed when the door is moved into its open position.

4. A stove provided with a pivotally mounted door, an arm projecting rearwardly from the hinged lower edge portion 55 of the door, a laterally-projecting pin on said arm, a compression spring arranged in a housing on the door frame located at the rear of the axis about which the door turns, and a rod projecting upwardly into said 60 spring and provided at its lower end with a fork or bifurcated portion that straddles said pin.

5. A stove, comprising a pivotally mounted door provided adjacent its lower edge 65 with a laterally-projecting trunnion, a rearwardly-projecting arm on said trunnion provided with a laterally-projecting pin, a spring housing on the door frame located at the rear of the axis about which the door 70 turns, and a vertically-disposed compression spring arranged in said housing between the upper end of same and said pin for counterbalancing the door when it is moving to and from its open position.

6. A stove provided with a pivotally mounted door, a compression spring for counterbalancing said door, a door frame provided with a housing for said spring located at the rear of the axis about which the 80 door turns, and a detachable section for said housing arranged flush or substantially flush with the front side of the door frame.

7. A stove provided with a pivotally mounted door, a compression spring for 85 counterbalancing said door, a door frame provided with a housing for said spring located at the rear of the axis about which the door turns, a detachable section for said housing arranged flush or substantially flush 90 with the front side of the door frame and provided at its upper end with a lug or hook that coöperates with the door frame to prevent the upper end of said section from swinging outwardly, and a bolt or other suitable fastening device for securing the lower 95 end of said section to the door frame.

HERMAN HERRENBRUCK.
FREDERICK ANDREAS.
